BALE TYING MECHANISM

Filed Aug. 5, 1927

UNITED STATES PATENT OFFICE

DWIGHT M. SIMPSON, OF CHARLESTON, SOUTH CAROLINA

BALE-TYING MECHANISM

Application filed August 5, 1927. Serial No. 210,909.

My invention relates to bale-tying mechanism, and particularly to such mechanism for use in presses.

One object of my invention is to provide a mechanism which may be applied to the presses now in use, and which will perform automatically several operations which have heretofore been carried out manually.

Another object of my invention is to arrange bale-tying mechanism within each division block so that the invention is applicable to presses now in use by a simple alteration of the press structure.

I will describe one form of bale-tying mechanism embodying my invention and will then point out the novel features thereof in claims.

In the accompanying drawing,—

Figure 1 is a broken view, taken substantially on the line 1—1 of Fig. 2, showing a division block embodying my invention;

Fig. 2 is a bottom view of the block shown in Fig. 1;

Fig. 3 is a sectional view showing the manner of using the block shown in Fig. 1;

Fig. 4 is a sectional view on the line IV—IV of Fig. 3; and

Fig. 5 is a bottom view partly in section showing the mode of operation of the block shown in Fig. 1.

Similar reference characters refer to similar parts in each of the several views.

Referring first to Figs. 1 and 2,—the reference character B designates a follower or division block, such as generally used in hay presses or similar machines, and comprising a plurality of strips 1 of wood, fastened to side posts 35 so as to form a rigid laminated frame structure. In practice it may be desirable to reinforce this frame with metal in order to provide bearing supports and to give the block rigidity, and such structure is within the purview of my invention. Pivots mounted about an axis 2 is a gear wheel 3, and meshing therewith are two small cog wheels 4 and 8 of substantially less thickness than gear wheel 3. The cog wheel 4 is rotatably mounted in two semi-circular races 5 and 6, these races being discontinuous, leaving an opening 7 and a similar opening through

which the cog wheel meshes with gear 3. In similar manner, the cog wheel 8 is mounted in two races 9 and 10 supported adjacent an opening 11 and an opening through which the teeth of the cog wheel mesh with the teeth of gear 3. A flexible cable 14 is arranged to rotate the gear wheel 3 in one direction, a handle 15 being attached to such cable and being supported from a suitable support 16. A coiled spring 12 is secured at its inner end to the axis 2 and at its outer end to a stationary post 13, so that when the handle 15 is released the spring operates to rotate the gear 3 and the cog wheels 4 and 8 to such a position that the tension is partially removed from the spring. Accordingly, when the handle 15 is pulled, the cable 14 operates to rotate the gear wheel 3 in one direction and also the cog wheels 4 and 8 in the opposite direction. Mounted on the opposite faces of the gear 3 are two flat steel cutting blades 17 and 18, the blade 18 being arranged to contact closely with the face of the cog wheel 8 when the gear 3 is rotated in a clockwise direction, and, similarly, the blade 17 cooperates with the cog wheel 4. In practice each of these cutting blades should extend over substantially as many teeth on gear 3, as there are teeth on the cog wheel with which it cooperates. The blades, moreover, are so arranged that they do not come in contact with their associated cog wheels until gear wheel 3 has made substantially a complete revolution.

Pivots mounted adjacent the openings 7 and 11 and near the bottom of the block B, are two wire guiding members 19 and 20, respectively. It should be noted that the openings 7 and 11 adjacent the cog wheels 4 and 8, respectively, are slightly off center with respect to these cog wheels for a purpose which will appear hereinafter.

Referring now to Fig. 3,—the reference character 21 designates the baling chamber of a press, here shown as of the type generally used in baling hay. This chamber is rectangular in cross section and carries above it the usual block setter 25 pivotally mounted at 26 and having an operating handle 27. A feed chamber 22 is arranged in rear of the

baling chamber 21 and a plunger 23 operated in any suitable manner cooperates to compress the hay within the baling chamber when it is fed into the feed chamber 22. Mounted 5 above and below chamber 21 are four spools of wire S, S¹, S² and S³, as best shown in Fig. 4. These spools are mounted in any suitable manner by means of supports E and each spool carries a reel of baling wire for 10 the purpose of tying the bales as they are formed in the chamber 21. The spools S and S² are mounted above the chamber 21, and the spools S¹ and S³ are mounted below the chamber, and each spool is provided with a ratchet 15 mechanism designated K with an exponent corresponding to the spool with which it is associated, which keeps the wire under tension and prevents it from feeding too fast and becoming slack when a bale is passing 20 through the baling chamber. This mechanism comprises a ratchet wheel 36, a pawl 37 and a spring 38 for pressing the pawl against the ratchet wheel. It will be clear from an 25 inspection of Fig. 3 that this mechanism allows the spool to rotate in a counter-clockwise direction when the wire is placed under tension but offers considerable resistance to such rotation.

The wires from the spools S¹ and S³ pass 30 through suitable openings in the bottom of the chamber 21 and over rollers X, which are provided for the purpose of guiding these wires and reducing the friction between the wires and the bottom of the chamber 21. 35 When the division block, such as B² shown in Fig. 3, is mounted on the block setter 25, the wires passing from spools S and S² pass through the slots 7 and 11, respectively, in the block, and due to the tension on the wire, 40 rotate the cog wheels 4 and 8 and the gear 3 to such a position that the wires are removed approximately 180° from the openings in which they enter. This action is due to the mounting of the cog wheels 4 and 8 slightly 45 off center and makes it possible to have the wires above the chamber reach slots between the cogs on cog wheels 4 and 8 in positions opposite to the openings 7 and 11 as best shown in Fig. 4. As shown in Fig. 3, the 50 chamber 21 contains a completed bale of hay 28 partially tied and a bale 32 which is completed ready for the first tying operation. These bales are separated by the division block B which is ready to perform the tying 55 operation, while a second division block B¹ has just been placed within the chamber before the bale 28 is forced out of the chamber by succeeding strokes of plunger head 23. A third division block B² is mounted in position 60 ready to be placed in the chamber 21 by the block setter 25 as soon as the next bale has been completed. It will now be clear that when the parts occupy the position shown in Fig. 3, the handle 15 in division block B 65 may be pulled in such manner as to rotate

the gears within this block and to twist the wires coming from above and below the chamber together to form ties, as indicated at 30 and 31. The specific manner in which this operation takes place is more clearly shown 70 in Fig. 5, in which the ties have been completed and the cutting blades 17 and 18 have severed one strand of the wire passing through the associated cog wheel. It will also be clear that this operation not only completes the tying and the separation of the bale 28, but at the same time ties and separates the bale 32, so that a single operation 75 completes the tying of the back end of the out-going bale and the front end of the entering bale. 80

The operation of the mechanism shown in Fig. 3, is as follows:—Assuming that the baling chamber 21 is empty, the wire from spool S is first drawn down and twisted together with the end of the wire coming from spool S¹. In a similar manner, the wire from spool S² is brought down and twisted with the end of the wire coming from spool S³. A small quantity of hay is then placed in the feed chamber 22 and forced back into the baling chamber 21 by operation of the plunger head 23, thus forming a backing for the first bale. After this operation is completed the division block is placed in position on the block-setter 25, and the wire from spool S is threaded through the slot 7, and in a similar manner the wire from spool S² is threaded through the slot 11. After this operation is completed, the division block is dropped into the chamber and hay is fed into the feed chamber 22 with the plunger-head 23 operating. During each stroke of the plunger the hay will be forced into the baling chamber 21 and the division block will be advanced through the chamber drawing with it against the tension of the spring restrained pawls on the spools, the wires from the upper and lower spools. A second block is now placed in position on the block setter and the wire is threaded through the slots in this block in the manner already described but, of course, there are in this instance no loose ends to be twisted together (see Fig. 4). When the first block which entered the chamber has proceeded far enough so that the signal is given for another block to be placed in the chamber, the block setter 25 is again operated and the second block is placed in the chamber. The tension on the upper wires passing from spools S and S² will be sufficient to rotate the cog wheels 4 and 8 in their raceways, and these wires will, therefore, pass to the side of these raceways opposite the slots and will remain there due to the tension of the wires. 115 120 125

As the second block enters the baling chamber the wire guides 19 and 20 will strike the bottom of the chamber and will rotate in such manner as to engage the wires coming from 130

spools S¹ and S³ and will carry these wires into the slots 7 and 11, respectively. Since the wires coming from the top spools are already passing through the notches in cog wheels 4 and 8, the wires coming from the lower spools will enter slots in these cog wheels at a position substantially opposite to that of the upper wires, but due to the tension on the upper wires, the relative positions of these two sets of wires will not be changed at this time. As the second block advances through the chamber it will eventually reach a position such that the tying operation for the outgoing bale and the incoming bale may be completed. Ordinarily, a signal bell is provided along the edge of the baling chamber to indicate to the man who feeds the press that it is time to insert another block, and this same signal may be used to indicate to the man who operates the bale-tying mechanism that it is time to tie up the rear end of the outgoing bale and the entering end of the incoming bale. When he receives the signal he will reach into the side of the chamber between the guides L on the side of the chamber and grasp the handle 15 and pull it outwardly until the cog wheels 4 and 8 have been rotated sufficiently to twist the ends of the wire together and the cutting blades 17 and 18 have been rotated far enough to completely sever the two wires associated with each tie. In order to enable the wires to be twisted together before the cutting blades contact with them, it is necessary that the gear wheel 3 make substantially a complete revolution before the cutting begins. From Fig. 1 it will be noted that when gear wheel 3 is rotated in a clockwise direction blade 17 must be advanced until its right hand end overlaps the cog wheel 4. It may do this without interfering with the wires passing between the teeth of cog wheel 8 because blade 17 is on the side of gear wheel 3 remote from cog wheel 8 (see Fig. 5) and this gear wheel is of greater thickness than the cog wheels so that the wires make a sharp angle with respect to gear wheel 3 and are thereby deflected away from the cutting blades except at the point where cutting contact is desired. As a result of this arrangement the two wires are twisted together before blade 17 encounters the wires passing between the teeth of cog wheel 4. In similar manner blade 18 does not encounter the wires associated with the cog wheel 8 until after substantially a complete revolution of gear wheel 3 takes place, and blade 18 may pass cog wheel 4 without cutting the wires associated with it. As soon as the handle 15 is released the coil spring 12 returns the handle to its position within the block, the operating mechanism is returned to the position shown in Fig. 1, and the block passes on through the baling chamber and outward along with the outgoing bale.

65 Although I have shown the bale-tying

mechanism as being adapted for manual operation, it is clear that any suitable mechanism may be provided for actuating this tying mechanism at the proper time. It will also be clear that by providing the proper ratio 70 between the cog wheels 4 and 8 and the gear 3, the distance through which the handle 15 must be pulled in order to complete the tying of the bales and the severing of the wires, may be made any desired amount. 75

The bale-tying mechanism which I provide may be readily used with the ordinary hay press by very slight modifications, and the same number of division blocks of the spool type which I have shown will be required as 80 is usual with the ordinary type of block. The handles projecting through these blocks may be positioned on any suitable part of the block in order to provide ready access thereto and such as to make it possible for one man to operate the feeding mechanism of the press and at the same time perform the tying operations 85 without the previous formation of bale ties.

It will, therefore, be clear that the mechanism which I provide not only renders it unnecessary for the wire to be cut into short lengths and looped, as with the usual type of press, but also makes it possible for one man 90 to perform all of the operations necessary to supply hay to the feeding chamber, to place 95 the division blocks, and to tie the bales.

Although I have herein shown and described only one form of bale-tying mechanism, it is understood that various changes and modifications may be made therein with- 100 in the scope of the appended claims without departing from the spirit and scope of my invention.

Having thus described my invention, what I claim and desire to secure by Letters Patent of the United States is as follows:

1. A division block for presses comprising a thin flat rectangular structure, a first gear rotatably mounted on said structure, a second gear meshing with said first gear and in the same plane therewith, said intermeshing gears being constructed and arranged to twist baling wires, a drum secured to said first gear, manually operable means carried wholly by said block for rotating said drum 110 in one direction to perform the twisting operation, automatic means for rotating said drum in the other direction, and wire cutting means carried by said first gear. 115

2. A division block for presses comprising a flat rectangular structure, a first gear rotatably mounted on said structure, a pair of spaced gears meshing with said first gear and in the same plane therewith, a drum secured 125 to said first gear, manually operable means for rotating said drum in one direction to rotate said gears and twist baling wires, automatic means for rotating said drum in the other direction, both of said rotating means 130

being carried wholly by said block and wire cutting means carried by said first gear.

3. A press comprising a baling chamber, spools of wire mounted above and below said chamber, a division block adapted to pass through said chamber and carrying a first gear rotatably mounted thereon, a wire receiving and twisting gear meshing with said first gear and arranged to contact with wires from above and below said chamber, means operable independently of said chamber for rotating said gears to twist said wires together, and wire cutting means associated with said first gear.

15 4. A division block for presses comprising a thin flat laminated frame, a first gear rotatably mounted in said frame, a pair of gears spaced from each other but meshing with said first gear and in the same plane therewith, wire guiding means associated with said frame for bringing the wires into engagement with the teeth of said pair of gears, means carried on said frame for rotating said gears to twist the wires together, a 20 pair of cutting blades on said first gear, one cooperating with each of said pair of gears, and spring means for returning said gears to normal position after the wires have been twisted and severed.

25 5. A division block for presses, including wire twisting and cutting mechanism and manually operable means for setting said mechanism into operation; said means and mechanism being entirely contained within 30 the confines of the block.

35 6. A division block for presses, including wire twisting and cutting mechanism, manually operable means for rotating said mechanism in a direction to twist and cut baling 40 wires, said block having a portion for receiving and guiding said manually operable means, and spring means for returning said mechanism to its initial position after the twisting and cutting operations are completed, all of said means and mechanism being contained within the outlines of the 45 block.

50 7. A division block for presses, including wire twisting and cutting mechanism, an actuating drum operatively associated with 55 said mechanism, and having a flexible member wound around it, a handle secured to said member for unwinding said member and rotating said drum and associated mechanism, said block having a cut-away portion to receive and guide said handle and render it accessible, and spring means for re-winding said member after operation of said mechanism, all of said means and mechanism being contained within the confines of the block.

60 8. A division block for presses comprising a thin rectangular frame, a primary gear mounted substantially centrally of said frame, means carried by said frame for rotating said gear, a pair of secondary gears

spaced from each other and meshing with said primary gear, all of said gears being in one plane, wire guiding means associated with said frame for bringing baling wires into contact with said secondary gears, two wire cutting blades carried by said primary gear, one on each side thereof and each co-operating with one of said secondary gears, said blades being spaced to allow the secondary gears to make a plurality of revolutions under the driving action of said primary gear before the cutting blades contact with their associated secondary gears to cut the wires, and spring means for returning said gears to their initial positions after operation thereof.

In testimony whereof I affix my signature
DWIGHT M. SIMPSON.
